UNITED STATES PATENT OFFICE.

ARTHUR SPARROW, OF CHICAGO, ILLINOIS, ASSIGNOR TO AMERICAN STEEL
FOUNDRIES, OF CHICAGO, ILLINOIS, A CORPORATION OF NEW JERSEY.

REVERSIBLE FULCRUM ARRANGEMENT.

1,425,064.

Specification of Letters Patent. Patented Aug. 8, 1922.

Application filed October 27, 1921. Serial No. 510,895.

To all whom it may concern:

Be it known that I, ARTHUR SPARROW, a citizen of the United States, residing at Chicago, in the county of Cook and State 5 of Illinois, have invented certain new and useful Improvements in Reversible Fulcrum Arrangements, of which the following is a specification.

This invention relates to brake beams and 10 more particularly to reversible fulcrums forming a part thereof.

The object of this invention is to provide a reversible fulcrum for the truss type of 15 brake beam, which fulcrum may be reversed between right and left-hand positions in a manner to meet service requirements and at the same time which provides a connection to the compression member of the brake beam without any longitudinal lost motion.

20 This and other objects are accomplished by means of the arrangement disclosed on the accompanying sheet of drawings, in which—

Figure 1 is a side elevation of a brake 25 beam fulcrum post, together with the tension and compression members of the brake beam shown in section;

Figure 2 is a fragmentary top plan view of the same brake beam; and

30 Figure 3 is a fragmentary rear elevation of the same.

The various novel features of the invention will be apparent from the following description and drawings and will be particularly pointed out in the appended claims.

35 Referring to the figures of the drawings, it will be noted that I have illustrated my invention in connection with a truss type of brake beam including a compression member 10, a tension member 11 and a reversible fulcrum post 12 interposed between and connecting same. This fulcrum post receives a brake lever, not shown, in the usual manner.

40 A rear portion 13 of the fulcrum post 12 extends between flanges 14 of the compression member 10, and has a rear surface 15 which is adapted to frictionally engage the front surface 16 of the web 17 of the compression member 10. This reversible fulcrum post 12 also has at its rear end a projection 18 which extends through an opening 19 in the web 17 of the compression member. This projection 18 is provided

with an opening 20 for the reception of a 55 wedge pin 21 whereby the rear surface 15 of the fulcrum post 12 will be pressed against the front surface 16 of the compression member web 17 for frictionally holding the fulcrum post 12 in its different adjusted 60 positions. It will be noted that the wedge pin 21 has a rear inclined surface 22 which engages the inclined rear wall 23 of the opening 20 and that the front surface 24 of the wedge key 21 is straight and parallel 65 with and engages the rear surface 25 of the web 17 of the compression member 10. It is apparent, therefore, that when the wedge 21 is driven into place the rear surface 15 of the fulcrum post 12 is tightly pressed 70 against the inner surface 16 of the web 17 of the compression member whereby the fulcrum post is frictionally held in adjusted position.

That portion 13 of the fulcrum post 12 75 between the flanges 14 of the compression member is provided with angular faces 26 for engaging said flanges 14 for limiting the fulcrum post 12 in its reversible movements.

The front portion of the fulcrum post 12 80 is provided with a tension rod saddle 27 having forwardly extending projections 28 so spaced and shaped to permit reversible movements of the fulcrum post 12.

It is my intention to cover all modifications of the invention falling within the spirit and scope of the following claims.

I claim:

1. In a brake beam, the combination of a compression member having a web portion, 90 a fulcrum post having a portion adapted to engage said web portion and having a projection extending beyond said compression member, and a wedge cooperating with said projection and compression member for 95 pressing said fulcrum post and web portion of the compression member into engagement for frictionally holding the fulcrum post in position.

2. In a brake beam, the combination of a 100 compression member having a web and flanges, a reversible fulcrum post having a portion interposed between the flanges of said compression member and adapted to engage the web thereof, said fulcrum post extending beyond said compression member, and means cooperating with said extending portion of said post and said compres-

sion member for forcing said fulcrum post into engagement with said web for holding said post in position.

3. In a brake beam, the combination of a compression member having a web and flanges, said web having an opening, a reversible fulcrum post having a portion interposed between said flanges and engaging the web, said fulcrum post having an apertured projection extending through an opening in the web of the compression member, and a wedge at the rear of the compression member extending through the opening in said projection for forcing the above mentioned portion of the fulcrum post into engagement with the web of said compression member for holding the fulcrum post in adjusted position.
4. In a brake beam, the combination of a compression member having a web and flanges, said web having an opening, a reversible fulcrum post having a portion interposed between said flanges and engaging the web, said fulcrum post having an apertured projection extending through the opening in the web of the compression member, a wedge at the rear of the compression

member extending through the opening in said projection for forcing the above mentioned portion of the fulcrum post into engagement with the web of said compression member for holding the fulcrum post in adjusted position, and means for limiting reversible movements of said fulcrum post.

5. In a brake beam, the combination of a compression member having a web and flanges, said web having an opening, a reversible fulcrum post having a portion interposed between said flanges and engaging the web, said fulcrum post having an apertured projection extending through the opening in the web of the compression member, and a wedge at the rear of the compression member extending through the opening in said projection for forcing the above mentioned portion of the fulcrum post into engagement with the web of said compression member for holding the fulcrum post in adjusted position, said fulcrum post and flanges cooperating to limit the reversible movements of said fulcrum post.

Signed at Chicago, Illinois, this 18th day of October, 1921.

ARTHUR SPARROW:
